UNITED STATES PATENT OFFICE.

FRANK M. McDONALD, OF LOS ANGELES, CALIFORNIA.

SURGICAL APPARATUS.

1,244,624.

Specification of Letters Patent. Patented Oct. 30, 1917.

Application filed July 11, 1917. Serial No. 179,800.

To all whom it may concern:

Be it known that I, FRANK M. McDONALD, a citizen of the United States, residing at Los Angeles, in the county of Los Angeles 5 and State of California, have invented certain new and useful Improvements in Surgical Apparatus, of which the following is a specification.

This invention relates to the class of 10 surgical appliances employed for removing obstructions from the nostrils, more particularly of young children, and has for one of its objects to provide a device which may be applied without discomfort to the patient 15 and operating to effectually remove obstructions from the nostrils and the passages leading thereto.

Another object of the invention is to provide a device whereby hard and refractory 20 substances or matter which gathers in the nostrils may be softened or reduced and then abstracted.

Another object of the invention is to provide a device whereby remedial agents, 25 either liquid, solid or powdered, may be conducted into the nostrils, all of these various operations being performed without structural change in the appliance.

With these and other objects in view, the 30 invention consists in certain novel features of construction as hereinafter shown and described and then specifically pointed out in the claims; and in the drawings illustrative of the preferred embodiment of the invention—

Figure 1 is a side elevation of the improved device;

Fig. 2 is a plan view;

Fig. 3 is a detail view of a part of the 40 appliance at right angles to the corresponding parts shown in Fig. 1, illustrating the construction and arrangement of parts more fully;

Fig. 4 is a detail view of an air pump 45 which may be employed instead of an air bulb when an increase of force is required;

Fig. 5 is an enlarged front elevation of the upper portion of the appliance, partly in section.

Fig. 6 is a section on the line 6—6 of 50 Fig. 5;

Fig. 7 is an enlarged sectional detail of the lower part of the air bulb portion of the device, illustrating the construction of the 55 holder for the remedial compound or material.

Corresponding and like parts are referred to in the following description and indicated in all the views of the accompanying drawings by the same reference characters.

The improved device comprises in general 60 a nose inclosing or receiving portion, represented as a whole at 10, a suction air bulb, represented at 11, a flexible tubular connection 12 between the bulb 11 and the nose inclosing portion 10, a receptacle for the matter extracted from the nose of the patient and represented conventionally at 13, and a tubular connecting branch 14 between the tubular member 12 and the receptacle 13. 65

The nose inclosing portion of the device 70 is preferably constructed of rubber or like material and provided with an enlarged margin 15 curved to closely engage over the upper outer portion or bridge of the nose 75 and the cheeks adjacent to the nose and likewise the upper lip between the nose and the discharge of the member 10, the discharge being located directly beneath the nostrils. The member 10 is provided with 80 flap-like attachments 16 at its sides from which straps 17 extend. A band to engage around the head of the patient forms a part of the improved device and is represented conventionally at 18, and is preferably 85 formed from leather or like material, relatively wide, and likewise preferably with longitudinal openings to lighten the band and also to increase its width. The member 18 is provided with buckles 19 at its ends 90 to be engaged with the straps 17, as illustrated in Fig. 1. By this means the device 95 may be readily clamped to the head of the patient and held in position over the nose. The member 18 is preferably lined with some soft fabric. Extending from the discharge end of the member 10 is a tubular neck portion 20 having a coupling member 100 21, preferably of metal, externally threaded, attached to its lower end. Located within the neck portion 20 is a transverse division member 22, the latter thus forming two longitudinal passages through the portion 20, as shown in Fig. 5. At its upper end, the member 22 is divided to form a socket 105 23 to receive the septum or dividing cartilage of the nose so that the passages of the nose communicate respectively with the passages in the appliance at either side of the partition. Located within the coupling 21 is an oblique partition 24, shown more clearly in 110 Fig. 5. At its upper end the tubular mem-

ber 12 is provided with a coupling member 25, preferably of metal, and adapted to be engaged with the coupling member 21. Formed within the tubular member 12 is a longitudinal partition 26 which merges into the tubular member 14, as shown in Fig. 5. The branch 14 of the tubular member 12 terminates at its lower end in a coupling member 27 to which a tubular extension 28, preferably of rubber is detachably connected.

The receiver 13 is detachably connected to the tubular member 28 by a coupling 29 which is preferably of metal, while the tubular member 12 is connected to the bulb 11 by a coupling member 30, also preferably of metal. The coupling members 27, 29 and 30 are substantially alike, and of the ordinary construction.

The nose receiving member 10, together with its partition 22-23, the tubular member 12, together with its branch 14 and partition 26, and the tubular connection 28, are preferably of flexible material, such as rubber, while the receiver 13 is constructed of some suitable material, such as glass, which will not be contaminated by the substance extracted from the nose. At its lower end the bulb 11 is provided with an annular internally threaded band 31 to receive a cup-shaped member 32 having an externally threaded flange to engage the threaded band and thus couple the member 32 detachably to the receptacle 11. The receptacle 32 is designed to contain a remedial substance or compound, as hereinafter described. An outwardly opening valve 33 of suitable construction is associated with the bulb 11, as shown in Fig. 7.

The receptacle 13 is provided with a detachable closure 34 so that the contents of the receptacle may be removed when required, and likewise to provide for the cleansing of the receptacle. An additional strap, a portion of which is represented at 39, may be connected to the member 10 to pass over the top of the head of the patient.

A double acting cut-off device is applied to the two-way conductor 20, while a similar cut-off device is applied to the two-way conductor portion 12-26, the cut-off devices being precisely alike so that the description of one will suffice for both. Each cut-off device comprises an open frame indicated as a whole at 35 and each supporting transverse pins 36 at opposite sides and each pin carrying a cam or pinch member 37 and an operating arm 38 adapted to be forced against the opposite sides of the portions 12 and 20 to compress the outer walls against the partition 22 or 26 as the case may be, as illustrated in Figs. 2 and 5, and thus "cut off" the flow through the conductor at either side of the dividing partition.

If one nostril only of the patient is clogged the passage through the member 20 associated with the unclogged nostril is closed by manipulating the cut-off device 37 associated with the passage, leaving the other passage open.

The improved implement, as before stated, may be employed either to draw obstructions from one or both of the nostril passages, or to inject medicinal matter into or through either or both nostril passages, and by manipulating the cut-off device either one or both of the nostril passages may be subjected to either a suction or drawing action to remove obstructions, or subjected to a forcing action to inject medicinal matter into either or both of the nostril passages.

It will also be obvious that air under pressure may likewise be forced through both or either one of the nostrils in the same manner. If it is desired to inject medicinal matter or compound only the cut-off device associated with the passage leading to the receptacle 13 will be closed and the bulb 11 manipulated to force the medicinal compound from the receptacle 32.

With a device thus constructed the operation is as follows:

If both nostrils of the patient are clogged and it is desired to merely remove the obstructions, the cut-off devices 37 associated with the conductor portion 12 are closed to shut off the flow of air, and the bulb 11 compressed to expel the air therefrom and thus create a partial vacuum in the bulb. The member 10 is then fitted over the nose of the patient with the septum or dividing cartilage of the nose in the socket 23, and secured in place by applying the straps 17-18-39, as before described. The cut-off members 37 are then opened, when a relatively strong suction will be produced through the nostrils by the air rushing into the empty bulb, the result being that any matter within the nostrils will be drawn into the passages formed by the partition 22 and deflected by the oblique partition 24 into the tubular member 14 at one side of the partition 26, and thence into the receptacle 13. The flow of the material will be observed through the transparent walls of the receptacle and, if a continued flow is necessary, the cut-off devices 36 associated with the passage leading from the bulb is again closed and the bulb exhausted as before described and the operation repeated, until the flow of material from the nostrils ceases, as observed in the transparent receptacle.

If it is necessary to apply medical compounds or material to the nostrils, the compound is deposited in the receptacle 32 and the valve 33 held closed by the pressure of the finger of the operator and the cut-off

36 opened and the bulb 11 compressed, with the result of forcing the medical compound into the nostrils.

If the suction produced by the bulb is not sufficient, the bulb can be replaced by an air pump indicated at 40 in Fig. 4, and any required suction force created thereby. If the matter in the nose is abnormally refractory, a softening compound may be forced 10 into the nostrils in the same manner as medicines are applied, and then the softened matter removed by suction as before described.

The pump will be employed only when 15 the substance or matter within the nostril is too refractory to be extracted by the relatively slight suction which it is possible to produce with the bulb. The mouth of the patient should be kept open during the operation of the device, and if the device is employed, upon very young children, a "pacifier" like device shown at 41 at the right of Fig. 1 will be inserted in the mouth through which the child can breathe when 25 the nostrils are shut off. The child is thus prevented from smothering during the operation of the device.

Having thus described the invention, what is claimed as new is:

30 1. A device of the class described comprising a member adapted to inclose the nose of a patient, a branching tubular conductor associated with the nose inclosing member, means for inducing air currents 35 through one of said branches, and a receptacle connected to the other branch.

2. A device of the class described comprising a member adapted to inclose the nose of a patient, a conductor leading from 40 the nose inclosing member and including passages connected respectively with the nostrils of the patient, independent means for cutting off the circulation through said 45 passages, a branching tubular conductor associated with the nose inclosing member, means for inducing air currents through one of said branches, and a receptacle connected to the other branch.

3. A device of the class described comprising a member adapted to inclose the nose of a patient, a branching tubular conductor associated with the nose inclosing member, means for inducing air currents through one of said branches, a receptacle 55 connected to the other branch, and a deflector operating to conduct material from the nose inclosing member into the passage leading to the receptacle.

4. A device of the class described comprising a nose receiving member, a branching tubular conductor leading from the nose receiving member, means for inducing air currents through one of said branches, means for controlling the flow of air

through said last mentioned branch, and a 65 receptacle connected to the other branch.

5. A device of the class described comprising a nose receiving member having a tubular discharge, a tubular conductor leading from the discharge of the nose receiving member, a transverse partition in said tubular conductor and deflected laterally at its upper end, means for inducing air currents through one of said branches, and a 70 receptacle connected to the other branch. 75

6. A device of the class described comprising a nose receiving member, a branching tubular conductor leading from the nose receiving member, an air bulb connected to one of said branches, a receptacle for a 80 medical substance connected to said bulb, and a receptacle connected to the other branch.

7. A device of the class described comprising a nose inclosing member, a branching tubular conductor leading from the nose inclosing member, means for securing said nose inclosing member to the head of a patient, means for inducing air currents through one of said branches, and a 85 receptacle connected to the other branch. 90

8. A device of the class described comprising a nose inclosing member having a tubular discharge, a branching tubular conductor leading from the tubular discharge, 95 means for inducing air currents through one of said branches and through the tubular discharge, and a receptacle connected to the other branch.

9. A device of the class described comprising a nose inclosing member having a tubular discharge, a branching tubular conductor leading from the nose inclosing member, means for inducing air currents through one of said branches and through 100 the tubular discharge, a lateral deflector in said tubular discharge, and a receptacle connected to the other branch. 105

10. A device of the class described comprising a nose inclosing member having a 110 tubular discharge, said tubular discharge being divided by a longitudinal partition, a branching tubular conductor leading from the tubular discharge, a lateral deflector in said tubular discharge and spaced from the lower terminal of the partition, means for inducing air currents through one of said 115 branches and through the tubular discharge, and a receptacle connected to the other branch. 120

11. A device of the class described comprising a nose inclosing member having a tubular discharge, a coupling member at the lower terminal of the tubular discharge and having a lateral deflector therein, a 125 branching tubular conductor having a coupling member engaging the coupling member of the tubular discharge, means for in-

ducing air currents through one of said branches, and a receptacle connected to the other branch.

12. A device of the class described comprising a nose inclosing member having a tubular discharge, said tubular discharge being divided by a longitudinal partition with a socket at the upper end of the partition adapted to receive the septum of the patient, a branching tubular conductor leading from the tubular discharge, means for inducing air currents through one of said branches, and a receptacle connected to the other branch.
13. A device of the class described comprising a nose inclosing member having a tubular discharge, said tubular discharge being divided by a longitudinal partition with a socket at the upper end of the partition adapted to receive the septum of the patient, a branching tubular conductor leading from the tubular discharge, means for independently cutting off the flow through the passages of the tubular discharge, means

for independently cutting off the flow 25 through the branching tubular conductor, means for inducing air currents through one of said branches, and a receptacle connected to the other branch.

14. A device of the class described comprising a nose inclosing member having a tubular discharge, a coupling member at the lower terminal of the tubular discharge and having a lateral deflector therein, a branching tubular conductor having a coupling member engaging the coupling member of the tubular discharge, means for independently cutting off the flow through the passages of the tubular discharge, means for independently cutting off the flow 30 through the branching tubular conductor, means for inducing air currents 35 through one of said branches, and a receptacle connected to the other branch.

In testimony whereof I affix my signature.

FRANK M. McDONALD. [L.S.]
